UNITED STATES PATENT OFFICE

SHELTON H. CONARROE, OF LAWRENCE, INDIANA, ASSIGNOR TO MULLINS MANUFACTURING CORPORATION, OF SALEM, OHIO, A CORPORATION OF NEW YORK

WEINGER

Application filed August 19, 1931. Serial No. 558,006.

The object of my invention is to produce a rugged and efficient clothes wringer, the parts of which may be readily fabricated and assembled at low cost, the construction being such that the upper roll may be readily associated with or disassociated from the lower roll and such that the upper roll may be quickly relieved from pressure, from either side of the device, by a comparatively small pressure applied by the operator in a direction toward the structure.

The accompanying drawings illustrate my invention:

Fig. 1 is a side elevation in partial axial vertical section of an embodiment of my invention;

Fig. 2 is an end elevation;

Fig. 3 is a vertical section on line 3—3 of Fig. 1;

Fig. 4 is a vertical section on line 4—4 of Fig. 1;

Fig. 5 is an end elevation of the upper roll unit;

Fig. 6 is a plan of one end of the lower roll unit;

Fig. 7 is a fragmentary section on the line 7—7 of Fig. 1;

Fig. 8 is a medial transverse section of a modification;

Fig. 9 is a section, similar to Fig. 3, of a modification; and

Fig. 10 is a fragmentary perspective of the drain pan receiving means.

In the drawings, 10 indicates a base 35 formed preferably of pressed sheet metal and comprising vertical standards 11, 11, each channelled to receive, guide, and support bearing blocks 12 in which is journaled the shaft 13 of the lower roll 14.

The standards 11, 11 are spaced apart a desired distance and are connected by a bib plate 15 preferably an integral part of the base, one on each side. The inner ends of plates 15 are connected and vertically distorted to form a trough 16 within which the lower roll 14 lies.

Mounted in the base on each side of the middle axial vertical plane are spring torsion bars 19, 19, each provided at its middle 50 with a non-rotative U-shaped bracket 20.

Each torsion bar 19 is rotatably supported in a pair of ears 21, 21 flanking the arms of the bracket 20 and bracket 20 is adjustably held against rotation in one direction by a set screw 22. The torsion springs may be 55 of any one of a number of forms but I have found in practice that each may be very satisfactorily made of a polygonal rod of steel, as indicated in the drawings, readily obtainable in the market at low cost. 60

Non-rotatively secured to the free end of each spring 19 is an arm 25 provided at its outer end with a pin 26 projecting axially of the rolls. The arms 25 at each end of the structure are projected toward each other 65 and their pins 26 lie in a horizontal slot 27 formed in the lower end of a vertically movable plate 28 guided for vertical sliding in the standards 11 by pins 29 carried by the base and projecting through vertical slots 70 30 in plate 28. This plate is medially slotted at 31 to permit the passage therethrough of the shaft 13 of the lower roll. Plate 28 near its upper edge carries an inwardly projecting pin 32 upon which is journaled a roller 75 33.

Slidably mounted in, and vertically removable from, standards 11 is a yoke 35, each depending arm of which carries an outwardly projecting shouldered pin 36 upon 80 which is pivoted a latch arm 37, the lower end of which is outturned to form a finger 38 adapted to take under the adjacent roller 33, said finger in its upper surface being provided with a shallow notch 39 serving to 85 position the latch 37 in vertical position.

The upper ends of the two latches 37 are anchored in the hollow head 40 which forms a cap over the upper ends of the standards 90 11 and a finishing cross head which the operator may readily grasp to manipulate the latches 37.

Vertically slidably mounted in the ways 45 carried by yoke 35, at each end of the yoke, is a bearing block 46 in which is journaled one end of shaft 47 of the upper roll 48. Each bearing block 46 is adjustable in yoke 35 by means of an adjusting screw 49. 95

When the parts are in the positions shown in full lines in the drawings, the cap 40 100

lies vertically over and covers the rolls and the upper open ends of the standards 11, and fingers 38 of latches 37 lie beneath rollers 33 and have pulled plates 28 upwardly, swing-
5 ing the adjacent ends of arms 25 upwardly and torsionally stressing the springs 19 so that the upper roll 48 is yieldingly urged upon the lower roll 14.

The operator, from either side of the ma-
10 chine, by a blow upon cap 40, may swing latches 37 upon their pivot pins 36 to withdraw fingers 38 from beneath rollers 33, thereby releasing the pressure upon the upper roll 48, whereupon the upper roll structure may be withdrawn upwardly from
15 the base, guides 45 and yoke 35 sliding upwardly in the standards 11.

To reassemble the parts, latches 37 are tilted, relatively to yoke 35, to the position
20 shown in dotted lines in Fig. 3, whereupon yoke 35 and its associated parts may be projected downwardly into standards 11 until roll 48 rests upon roll 14, at which time fingers 38 have descended to a position
25 where, upon swinging latches 37 upon their pivot pins 36, the fingers 38 may be projected beneath the rollers 33 to draw said rollers and their associated plates 28 upwardly to restress the torsion springs.

30 By utilizing torsion springs of the character illustrated in the drawings the cost of production is very greatly reduced and it is possible to produce a wringer, the overall height of which is substantially less
35 than has been heretofore commercially practical, without sacrifice of sufficient leverages to permit establishment and release of roll pressures by the exertion of a comparatively small amount of force well within the
40 physical capacity of the average woman operator.

It will be noted that the opposite ends of each spring 19 function independently and, of course, independent springs might be provided without departing from my invention.

45 It will also be readily understood that a single torsional spring at each end of the structure, if sufficiently strong, would be sufficient but I believe that the arrangement shown is more satisfactory because of the possible balancing of stresses.

Referring to Fig. 8, the bibs 15 have down turned inner edges 15' to which are welded the upper edges of the trough piece 16'.

50 Instead of notching the fingers 38 at 39, as shown in Fig. 3, the notches may be omitted and the head 40 normally held in medial position by a spring 60 the ends of which are retained under the inturned edges 40' of head 40 and the middle of which is distorted to form a pocket 61 (flanked or defined by rounded ribs 62, 62) adapted to yieldingly receive and retain the middle of yoke 35. The reversible drain pan 70 is removably bolted, by bolts 71, to brackets 72

which are conveniently rivet-pivoted to ears 73 of the trough piece 16'. Pan 70 is provided with a segment arm 74 having teeth which mesh with the teeth 75 of a split sleeve 76 frictionally clamped on the shaft of the 70 lower roll by a spring ring 77.

Fig. 9 shows a modified connection between latch arm 37 and the springs 19. In this construction the vertically movable plate 28' (slotted at 31 to receive the lower 75 shaft 13) is slidable in guides 63 and is provided with pins 26' which take into slots 27' formed in the levers 25' carried by springs 19. Plate 28' is provided with a roller 33 as in the form shown in Figs. 1 and 3. 80

Each lever 25' is provided with an arm 25'' carrying an adjustable temper screw 65 normally engaging the base frame so as to prevent roller 33 from being moved below the range of movement of finger 38. 85 By means of this construction springs 19 may be placed under any desired initial stress by adjustment of temper screws 22 without carrying rollers 33 out of range 90 of engagement of fingers 38.

I claim as my invention:

1. In a wringer, a base, a roll journaled therein, a second roll journaled in the base and transversely movable relative to the first roll, a torsion spring, an anchorage for one end of said spring associated with one of said rolls, and means associated with the other of said rolls for separably engaging said spring to place it by engagement therewith under torsional stress yieldingly opposing transverse displacement of the rolls relative to each other. 95

2. In a wringer, two mating roll supports vertically separable, two rolls, one journaled in each of said supports, two torsion springs 100 anchored on one of said supports with their free ends adjacent opposite ends of the rolls, latching means carried by the other of said supports adjacent the opposite ends of the rolls and mounted to swing upon an axis 110 parallel with the roll axes, and means comprising radially extending arms carried by the free ends of the torsion springs, for separable engagement by the latching means to place said springs under torsional stress 115 urging one roll upon the other.

3. In a wringer, two mating roll supports vertically separable, two rolls, one journaled in each of said supports, two torsion springs anchored on one of said supports with their free ends adjacent opposite ends of the rolls, latching means carried by the other of said supports adjacent the opposite ends of the rolls, and means comprising radially ex- 120 tends arms carried by the free ends of the torsion springs, for separable engagement by the latching means to place said springs under torsional stress 125 urging one roll upon the other.

4. In a wringer, a base, a lower roll jour- 130

- nailed therein, an upper roll associated with the lower roll, two torsion springs anchored in the base with their free ends respectively adjacent the ends of the lower roll, a radially 5 projecting arm carried by the free end of each of said springs, two latches associated with the upper roll, one adjacent each end thereof, and mounted to swing upon an axis parallel with the roll axes, a connection between 10 said latches, and a separable connection between said latches and the spring arms serving to torsionally stress said springs to urge the upper roll toward the lower roll.
15. 5. In a wringer, a base, a lower roll journaled therein, an upper roll associated with the lower roll, two torsion springs anchored in the base with their free ends respectively adjacent the ends of the lower roll, a radially 20 projecting arm carried by the free end of each of said springs, two latches associated with the upper roll, one adjacent each end thereof, a connection between said latches, and a separable connection between 25 said latches and the spring arms serving to torsionally stress said springs to urge the upper roll toward the lower roll.
6. In a wringer, a base, a lower roll journaled therein, an upper roll associated with the lower roll, two torsion springs anchored in the base with their free ends respectively adjacent the ends of the lower roll, a radially 30 projecting arm carried by the free end of each of said springs, two latches associated with the upper roll, one adjacent each end thereof, a connection between said latches, and a separable connection between 35 said latches and the spring arms serving to torsionally stress said springs to urge the upper roll toward the lower roll.
7. In a wringer, a base, a lower roll journaled therein, an upper roll associated with the lower roll, two torsion springs anchored in the base with their free ends respectively 40 adjacent the ends of the lower roll, a radially projecting arm carried by the free end of each of said springs, two latches associated with the upper roll, one adjacent each end thereof, a connection between said latches, and a connection between said latches and the spring arms serving to torsionally stress said springs to urge the upper roll toward 45 the lower roll.
- 45 adjacent the ends of the lower roll, a radially projecting arm carried by the free end of each of said springs, two latches associated with the upper roll, one adjacent each end thereof, and mounted to swing upon an axis parallel with the roll axes, a connection between 50 said latches, and a connection between said latches and the spring arms serving to torsionally stress said springs to urge the upper roll toward the lower roll.
55. 8. In a wringer, a base, a lower roll journaled therein, an upper-roll yoke, an upper roll journaled therein vertically slidably associated with the base, two latches, one pivoted upon each end of said yoke upon an 55 axis parallel with the roll axes, a connection between said latches, two torsion springs anchored in said base with their free ends adjacent the ends of the lower roll, a radial arm non-rotatively carried by the free end 60 of each spring and projected toward the medial vertical plane of the base, a vertically 70 slideable plate associated with the adjacent spring arms and provided at its upper end with a projection engageable by the adjacent latch, substantially as described.
9. In a wringer, a base, a lower roll journaled therein, an upper-roll yoke, an upper roll journaled therein vertically slidably associated with the base, two latches, one pivoted upon each end of said yoke upon an 75 axis parallel with the roll axes, a connection between said latches, four torsion springs anchored in said base with their free ends adjacent the ends of the lower roll, a radial arm non-rotatively carried by the free end of each spring and projected toward the medial vertical plane of the base, a vertically 80 slideable plate associated with the adjacent spring arms and provided at its upper end with a projection engageable by the adjacent latch, substantially as described.
10. In a wringer, a base, two rolls associated with said base and one movable transversely toward and from the other, a pair of 85 spring units anchored in the base and extending substantially parallel with the rolls one on each side of the vertical plane of the roll axes, and means between the free ends of said springs and the transversely movable roll by which said springs may be stressed upon and released from the transversely 90 movable roll.
11. In a wringer, a base, two rolls associated with the base and one movable transversely toward and from the other, a pair of torsion spring units anchored in the base and extending substantially parallel with the rolls one on each side of the vertical plane of the roll axes, radial arms carried by the free ends of said springs, and means 95 between said arms and the transversely movable roll by which said springs may be torsionally stressed upon and released from the transversely movable roll.
12. In a wringer, a base, two rolls associated with the base and one movable transversely toward and from the other, a torsional spring anchored in the base, a slide vertically reciprocable in the base, intermediate connections between the slide and spring whereby displacement of the slide in one direction will torsionally stress the spring, and a connection between said slide and one of the rolls.
13. In a wringer, a base, two rolls associated with the base and one movable transversely toward and from the other, a torsional spring anchored in the base substantially axially parallel with the lower roll, a slide vertically reciprocable in the base, intermediate connections between the slide and spring whereby displacement of the slide in one direction will torsionally stress the spring, and a connection between said slide and one of the rolls.

14. In a wringer, a base, two rolls associated with the base and one movable transversely toward and from the other, a torsion rod anchored in the base, a radially-extending arm carried by the free end of said rod, a vertically-movable slide mounted in the base, a connection between said slide and one of the rolls, and a connection between said slide and said radially-extending arm whereby movement of the slide in one direction will develop torsional stress in the rod.
15. In a wringer, a base, two rolls associated with the base and one movable transversely toward and from the other, a torsion rod arranged substantially parallel with the rolls and anchored at its middle in the base, two radially-extending arms carried respectively by the free ends of the torsion rod, two slides slidably mounted in the base and connected respectively with said radially-extending arms, and connections between said slides and one of the rolls whereby transverse displacement of said roll relative to its fellow will develop torsional stress in the torsion rod.

In witness whereof, I have hereunto set my hand at Indianapolis, Indiana, this 7th day of August, A. D. one thousand nine hundred and thirty-one.

SHELTON H. CONARROE.
